DESIGN FOR A DRESS

Joan Bayor, New York, N. Y.

Application September 2, 1937, Serial No. 71,424

Term of patent 3½ years

To all whom it may concern:

Be it known that I, Joan Bayor, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

Figure 1 is a front view of a dress showing my new design.

Figure 2 is a rear view of the dress shown in Figure 1.

Figure 3 is an enlarged view of the sleeve member of the dress, as seen from the side.

The characteristic feature of my design resides in the combination on the dress as shown of the buttoned-on corded floral ornaments at the neckline and pocket portions, as shown.

I claim:

The ornamental design for a dress, substantially as shown, and described.

JOAN BAYOR.
